DESIGN FOR AN OPEN-FRONT STOVE.

SPECIFICATION forming part of Design No. 21,228, dated December 8, 1891.

Application filed November 12, 1891. Serial No. 411,742. Term of patent 7 years.

To all whom it may concern:

Be it known that I, FRANCIS RITCHIE, a citizen of the United States, and a resident of Troy, Rensselaer county, New York, have 5 invented a Design for an Open-Front Stove, of which the following is a specification.

My design for an open-front stove is fully illustrated in the accompanying drawing, the view in which represents the face of the stove. 10 The main feature of the design is the ornamentation of scroll-work on the doors and frame and on the columns at each side of the stove.

A is the base of the stove, the legs a of 15 which are ornamented by scrolls, as shown, and supported on the base is the body portion B, having at each side columns b, ornamented throughout their length by feather scroll-work, and at the base and at the top of each 20 column are scroll-rosettes c.

On the projecting front is a dome D, ornamented by scrolls extending from the center toward each side, and above the dome on the flat portion of the stove at each side of the center are scrolls d d.

The doors E and F are ornamented by scrolls which cover the openings, as shown.

The dome g on the top G of the stove is ornamented in keeping with the rest of the design, and mounted on this dome is an ornamented urn h.

Between the two doors E and F and extending across the stove is an ornamental plate e, and below this plate is a bar f, having a series of small scrolls.

I claim—

The design for an open-front stove, substantially as described, and as shown in the accompanying drawing.

In testimony whereof I have signed my 40 name to this specification in the presence of two subscribing witnesses.
